Primary Examiner — Mark Goodwin(74) *Attorney, Agent, or Firm* — Michael Best & Friedrich
LLP(57) **CLAIM**I claim the ornamental design for a cab module, as shown and
described.**DESCRIPTION**FIG. 1 is a perspective view of a cab module showing my new
design.

FIG. 2 is a front view of the cab module shown in FIG. 1.

FIG. 3 is a rear view of the cab module shown in FIG. 1.

FIG. 4 is a right side view of the cab module shown in FIG. 1.

FIG. 5 is a left side view of the cab module shown in FIG. 1.

FIG. 6 is a top view of the cab module shown in FIG. 1; and,

FIG. 7 is a bottom view of the cab module shown in FIG. 1.
The broken lines shown in the drawings are for illustrative
purposes only and form no part of the claimed design.**1 Claim, 7 Drawing Sheets**## U.S. PATENT DOCUMENTS
